UNITED STATES PATENT OFFICE

2,530,542

HOLDER FOR COMBS

Lester T. Sawyer, Leominster, Mass.

Application August 8, 1946, Serial No. 689,294

1 Claim. (Cl. 206—79)

1

This invention relates to a holder for combs such, for example, as the type shown in Patent No. 1,684,362 granted to me September 11, 1928.

For the purpose of advertising and sale, combs of the above type are usually mounted on a holder consisting of a sheet of flexible fiberboard having struck-out tabs which interlock with the teeth so as to hold the comb in place. An objectionable feature of this type of holder is that the corners of the comb, particularly the pointed free ends of the teeth, are not enclosed or otherwise protected and in handling a group of holders the corners of the comb are apt to catch on one another or on the holders with the result that the combs may become dislodged or the holders become torn or otherwise injured.

The principal object of the present invention is to provide a holder which is of simple design, economical to manufacture, capable of being readily assembled with combs of the aforesaid type, and which overcomes the aforementioned difficulties.

Further objects will be apparent from a consideration of the following description and the accompanying drawings, wherein—

Fig. 1 is a plan view of a holder constructed in accordance with the present invention and showing a comb mounted on one of its two sections;

Figs. 2 and 3 are side and end views, respectively, of a holder carrying a pair of combs; and

Fig. 4 is an enlarged section on the line 4—4 of Fig. 1.

The embodiment herein shown for the purpose of illustration comprises a rectangular sheet of flexible fiberboard 1 or other suitable sheet material of a size sufficient to hold one or more combs with sufficient space above the combs to receive a trade mark or other advertising matter. The holder herein shown is designed to receive a pair of combs C, and hence is formed with two identical sections. Each section is formed with a pair of spaced slits 3 and 4 which delineate an area slightly larger than that of the comb to be held. The upper part of each of the slits is generally U-shaped so as to define rearwardly bendable panels 5 and 6 which, when bent rearwardly, provide recess portions for receiving the opposite lateral edges of the comb, as shown more closely in Figs. 2 to 4.

The lower or outer ends of the slits 3 and 4 extend outwardly and are shaped so as to define a pair of locking tabs 8 and 9 and also a pair of rearwardly bendable ears 11 and 12 which, when bent rearwardly, provide recesses for receiving the pointed free ends of the teeth at the opposite ends of comb C, as illustrated in Figs. 2 and 3.

Preparatory to mounting a comb C on the

2

holder, the mid-portion of each of the locking tabs 8 and 9 is bowed or bulged outwardly, and the comb C is then applied so that its outer or end teeth pass through the bowed portion as shown in Fig. 4. The comb is then adjusted so that the opposite ends of its arcuate back press the panels 5 and 6 rearwardly so that the ends of the back are disposed within the recess portions defined by the panels 5 and 6; and its outer teeth likewise press the ears 11 and 12 rearwardly so that their pointed ends are disposed within the recessed areas defined by the depressed ears 11 and 12, as shown in Figs. 2 and 3. It will be noted that the four corners of the comb are thus disposed below the marginal portions surrounding the slits 4 and 5 and where, as here shown, the combs are formed with teeth having resilient contiguous portions, the locking tabs are firmly gripped, as shown in Fig. 4 and hence the combs are firmly secured to the holder.

While I have shown and described one desirable embodiment of the invention it is to be understood that this disclosure is for the purpose of illustration and that various changes and modifications may be made without departing from the spirit and scope of the invention as set forth in the appended claim.

I claim:

30 An article of manufacture comprising in combination a rectangular-shaped comb of concavo-convex contour, and a holder consisting of a sheet of flexible material formed with spaced slits shaped and arranged to define the corner portions of a generally rectangular area approximating the size of said comb, said corner portions being bent into offset position relative to the surrounding parts of said holder to provide recesses receiving the corner portions of said comb, the intermediate portions of said slits extending toward each other and transversely of the end teeth of said comb to provide holding tabs bent into interlocking relation with the end teeth of said comb to hold it firmly in position within said area and with its corner portions within said recesses.

45 LESTER T. SAWYER.
